(57) **CLAIM**

The ornamental design for a cabinet with retractable stool, as shown and described.

DESCRIPTION

FIG. 1 is a perspective view from above of a cabinet with retractable stool, with a stool in an extended position and doors in closed position, showing my new design;

FIG. 2 is a front view thereof, with doors in closed position;

FIG. 3 is a left side view thereof, with the stool in an extended position;

FIG. 4 is a top view thereof, with the stool in an extended position;

FIG. 5 is a right side view thereof, with the stool in an extended position;

FIG. 6 is a back side view thereof;

FIG. 7 is a bottom side view thereof, with the stool in an extended position;

FIG. 8 is a perspective view from above of the cabinet with retractable stool, with the stool in an extended position, and fitted with a sink and facet on its top surface; and,

FIG. 9 is a perspective view from above of the cabinet with retractable stool, with the stool in an retracted position, fitted with a sink and facet on its top surface, and with the cabinet door in an opened position.

The broken lines shown are for illustrative purposes only and form no part of the claimed design.
